COMBINED HOSPITAL BED LAMP AND SERVICE CONSOLE UNIT AND EXTENSIBLE READING LAMP

Marcus Bodian, Los Angeles, Calif., assignor to Sunbeam
Lighting Co. Inc., a corporation of California

Filed Sept. 12, 1966, Ser. No. 3,808

Term of patent 14 years

(Cl. D48—20)

FIG. 1 is a front elevational view of my combined hospital bed lamp design including the service console unit and extensible reading lamp;

FIG. 2 is a top plan view of the same;

FIG. 3 is a bottom plan view of the same;

FIG. 4 is a side elevational view taken from the position of line 4—4 of FIG. 1; and

FIG. 5 is an elevational view taken from the position of line 5—5 of FIG. 1.

The rear of design is substantially plane and unornamented.

I claim:

The ornamental design for a combined hospital bed lamp and service console unit and extensible reading lamp, as shown.
